ABSTRACT OF THE DISCLOSURE

A fixed resistor of thin sheet or film form having opposed edges, between feed points on which a voltage may be applied to produce current flow along a current axis between the points and through the body of the resistor, at least one of these edges being shaped as an integral triangular projection extending at 30 to 45 degrees from the current axis to a pointed terminal at the tip of which the potential gradient is very low and a voltage proportional to the applied voltage may be tapped; one form is basically a rectangle from whose sides segments are removed to leave concave margins symmetric about the axis, permitting electrical ganging of the tips of cusps bounded by the margins which are at like potential.

This invention relates to fixed resistors, and the object I have in view is to provide a precision sheet resistor having its margins shaped to provide one or more integral tapping projections shaped as elongate points extending in directions which make acute angles with respect to a current flow axis, whereby the distribution of equipotential lines in the terminal area of the point assures low potential gradients in such area. Resistors so constructed permit connections to be made with the ends of such projections with insignificant errors in the measurement of potential arising from small variations in the position of the connection at the point.

Resistors constructed according to the invention and having at least one tapping projection are useful when connected in series as voltage divider chains to obtain precise voltage subdivision at connecting taps.

Resistors formed as symmetrical sheet bodies and having at least one pair of tapping projections according to the invention are especially useful as precise meter shunts.

It is well known that resistors made from a sheet of resistive material of uniform thickness, if exactly similar to each other in all respects except the scale of their plan form, will have identical resistance for a given temperature. The resistors according to the present invention likewise exhibit constant resistance regardless of the scale of their plan area, and moreover the symmetrical sheet forms of resistor exhibit a substantially constant impedance which is independent of frequency up to hundreds of megacycles per second.

If a given current is passed through a flat sheet resistor shaped as a square, along a current axis bisecting opposed sides of the square, the distribution of current will be such that the density along the axis is highest, falling off to each side of the axis and being minimum along the other two sides. The equipotential lines may be readily plotted, the lines forming an orthogonally related pattern with the plot of current flow lines, among which will be found a certain potential whose locus intersects the pair of corners lying on opposite sides of the current axis. This locus also intersects the current axis at a point intermediate one current connection point and the midpoint of the resistor. It will also be found that on either side of this equipotential curve in the vicinity of the corner point the gradient is lower than at any other area along the margins. Nevertheless, small differences in the position

2

of a connector such as a test prod applied to the corner will produce substantial discrepancies in potential measurements.

I have found that when the margins of a sheet of resistive material are arcuately shaped to provide a resistor having two orthogonally related pairs of opposed concave margins, and current is passed through the resistor body so defined by way of current feed points located at the ends of a current axis bisecting the sheet and also bisecting each margin of an opposed pair, that the plot of equipotential lines in the cusps formed by the junctions of adjacent margins exhibits very low potential gradient, particularly in the vicinity of the point of the cusp. When the margins have arcuate form and all have the same radius of curvature and are generated on centers lying equidistant from the center of the body, a pair of centers being located on a respective axis of a pair of axes which are at right angles, a highly precise resistor will be realized, wherein either axis may be chosen as the current axis. The potential difference between that pair of cusps lying on the same side of the current axis, or between either pair which lie diagonally opposite each other, is substantially a constant fraction of the applied voltage at the current feed points, and will depend on the concavity of the margins; for example, when the margins are circularly concave as described above, the voltage difference is about 28% of the applied voltage. The same potentiometric ratio will be obtained regardless of the scale to which the resistor is made, if the thickness, resistivity, and temperature are held constant over the whole area of the resistor. If a constant current is passed between the current feed points, the potential difference established will depend on the variation of any one parameter when the others are held constant.

The resistor body may have its concave margins defined by curves other than circular arcs; for example, these may be defined by parabolae, hyperbolae, ellipses, or any symmetrical oval indentation. Moreover the marginal outlines may be produced by combinations of straight lines, disposed at various angles in simulation of a regular curve, provided that in all forms the elongate tapering point or cusp is extended in a direction which forms an acute angle with the current axis.

Moreover, the margins of the resistor body may be generated by curves or lines so that while the body may be symmetrical if folded about the current axis, it is not necessarily similar when folded about a midline which is at right angles to the current axis.

Such resistors afford a high tolerance to off-axis positions of current feed connections, when the pair of potential differences at the ends of respective diagonals between cusps are averaged to provide a mean difference.

The invention may be the better understood from a reading of the following description of its preferred embodiments together with the accompanying figures of drawing, in which:

FIGURE 1 is a plan view of the resistor body according to the invention having its margins geometrically defined by circular arcs, showing current axis and a plot of equipotential lines;

FIGURE 2 is a cross-section taken on a transverse axis along line 2—2 of FIGURE 1;

FIGURE 3 shows a similar body having its margins defined by identical parabolae;

FIGURE 4 shows a resistor body having the margins formed by straight lines, and the tapering points extended at about 40° with respect to the current axis;

FIGURE 5 shows a resistor as in FIGURE 1 wherein the position of one of the current feed points is displaced from the axis;

FIGURE 6 is a graph plotting error in the mean potential difference observed for the device of FIGURE 5;

FIGURE 7 shows a pre-assembly perspective detail of a notched current junction for solder connection of adjacent series-connected metal sheet resistors;

FIGURE 8 is a side elevation view of a self supporting train of metal resistors as in FIGURE 7, having a common current axis;

FIGURE 9 shows a chain of identical deposited film resistors each having a single elongate tapering point leading to a respective tapping connection of a precision voltage divider; and,

FIGURE 10 shows a chain similar to that of FIGURE 9 wherein each resistor is a symmetrical body having pairs of like-potential cusps ganged by low resistance buses.

The resistor sheet generally designated 10 in FIGURE 1 has a current axis 11 and a transverse axis 12 intersecting at a center point 13. The opposed margins 14, 15 are circular arcs having centers 16, 17 in the axis 11, and the other margins 18, 19 have centers 20, 21 in the axis 12. Current feed points 22 and 23 lie at the intersection of axis 11 with the margins 14 and 15.

The symmetrical body 10 thus generated has four cusps, the points of which are 24, 25, 26 and 27, bisected by the diagonal 28, 29. It will be apparent that the body essentially comprises the inscribed square 30 indicated by dashed outline, having four like segments removed. Each radius r should be one-half the distance between a pair of centers designated 16 and 21. The body is well adapted for precise fabrication as when a square blank sheet 30 has its margins sheared to produce concave edges by means of circular punch and die tools, the square being rotated about a center 13 and indexed in positions 90° apart.

The equipotential lines which may be plotted on the surface of the resistor include a curved line 31 which intersects the axis 11 at the point 32, and which extends into the points of the cusps. The adjacent equipotential lines 33, 34 which run into the cusp margins at points spaced from the tip intersect the axis 11 at points indistinguishably close to the point 32, when the interval is taken as about one percent of the voltage difference between feed points 22 and 23. Consequently, tapping connections made with the point may vary appreciably in physical position without introducing significant error in a measurement of the potential at the tip of the cusp.

In the device of FIGURE 3, the parabolic indentations are formed by opposed parabolae 35. The point of each cusp lies theoretically at infinity, but practically may be taken as the intersection of dashed lines outlining the square 30, the sides of which intersect axes 11 and 12 at right angles; for example each side may be the latus rectum of a parabola. The breadth of each cusp decreases more gradually toward the tip than in the device of FIGURE 1.

The margins 14, 15 of the device of FIGURE 4 include triangular projections 37, 38, 39, 40, having cusp points as in FIGURE 1 and the current feed points 22 and 23 lie on short transverse straight line edges. The bisectors 50 make acute angles of about 40° with the current axis 11. The potential difference between the cusp points which are on the same side of the current axis or between cusps lying diagonally opposite each other is somewhat greater in this embodiment than the difference observed for the FIGURE 1 embodiment, due to the increased ratio of length to width of the resistor and the smaller angle made by the bisector 50. It will be understood that as the length of the resistor is increased in relation to the breadth as measured along the transverse axis 12, a proportionately greater fraction of the applied voltage will be manifested between cusp points such as 25 and 26. The triangular projections may be disposed so that their apical bisectors form acute angles smaller or larger than 40°, for example in the range 30° to 50°.

While it would be expected for a precisely symmetrically shaped resistor that the voltage differences between diagonally opposite cusp points should be identical if the current feed points lie precisely on the junction of axis 11 with the end margins, in practice some variations are ob-

served, due largely to the nature of the current connections. It is extremely difficult to make a solder connection which is a perfectly symmetrical body of rotation about the axis 11 with a marginal edge. However as shown by FIGURES 5 and 6, the current feed points may have substantial off-axis positions, such as represented by a test current leads 22A offset to the right of the axis by one thickness t of the resistor sheet and by the group of leads 22B-D offset to the left by unit distances each equal to twice the sheet thickness. Inspection of the observed variation of potential between diagonally opposed pairs of cusp points 24-27 and 25-26 reveals that when these are averaged, the error of the mean is far lower, and over a range of offsets equal to a small multiple of the sheet thickness becomes negligible. Accordingly, for the highest precision of potential tapping the means potential difference should be relied on even though the current feed points appear to be accurately located. Such averaging also minimizes errors due to non-homogeneity of the resistor and variations of thickness or temperature over the area of the resistor body.

In FIGURE 7 the margins 14 and 15 are shown notched, each notch 14A and 15A having a width and depth approximately equal to the thickness t of the sheet, the drawing exaggerating the thickness dimension for clarity. Nevertheless, metal resistors of considerable thickness may be employed in high-current, low-voltage divider trains, the thickness being not greater than about 0.15 times the minimum breadth measured along axis 12. Such junction provides a good mechanical joint and may be reinforced by a drop of soft solder, silver solder, or brazing metal, as at 41 in FIGURE 8. The voltages between adjacent like-potential points of the train, designated 25, 25', 25" . . . will show a constant difference so that the chain may serve as a decade resistor or in any application requiring precise subdivision of an applied voltage in constant unit steps.

In the resistor train of FIGURE 9 each element 10A comprises an area bounded by edges each of which is comprised by a circular arc merging with a straight line portion. Only two diagonally opposed cusps extend from the body, one being formed by arcs 14A and 19, the other by arcs 18 and 15. Straight line portions 14A, 18A, and 19A, 15A lie on a rectangle with which the arcs are merged. The cusps may also be bounded by curved lines other than circular arcs. The material coating each area may be any one of the known resistive materials that may be deposited or printed on a supporting base sheet 43, and may include relatively thin metallic or metal alloy films of high resistivity. Current feed points secured in the base sheet and permanently connected with each resistor element comprise posts or solder electrodes 122 and 123. Similarly the cusp points 125 are provided with leads at which potentials may be measured along the train. It will be evident that the resistor body 10A is neither symmetrical if folded about the current axis or about a transverse axis through the midpoint of the resistor. Nevertheless, the potential gradient in the vicinity of the point of the cusp will be low so that readings of voltage will be relatively accurate.

The resistor films may be deposited as a group by known printing techniques, even when the physical dimensions of the resistors are extremely small, so that a relatively precise voltage divider system may be realized at low cost. It is to be noted that the terminal body 125 may comprise a relatively broad low-resistance metal post or deposited conductor spot, connected with the pointed extremity of the cusp portion so that external connections cannot introduce gradient error.

In the train of FIGURE 10, the elements are either stamped conductive sheets or printed films, provided with an axis of symmetry 11 and the elements being spaced to avoid interference between their cusps, and having low-resistance bus or metal connector deposits 44 joined between their current feed points. Similarly, and preferably

on that side of the base sheet opposite to the side along which the current connections are led, the pair of like-potential cusp points are ganged by transverse low-resistance conductors 45. Such train will obviously permit a greater current to be tapped at the cusp points without affecting the potential distribution. While the particular embodiment shown comprises elements having concave margins of like radius and the potentials are indicated along the train for such form of elements, it is to be understood that any of the forms described hereinabove having symmetry about the current axis may be used.

It is to be understood that the surface area of each resistor element should be chosen to provide adequate heat dissipation. Since the resistance of the element is a parameter independent of the scale in plan, provided thickness and resistivity is held constant, it will be evident that extremely small area elements made of uniformly thin films of high resistivity may be fabricated having resistance values from a fraction of an ohm to hundreds or thousands of ohms. As the scale of the element is reduced, the accuracy of the tapping connections becomes inherently greater by comparison with prior resistor forms.

I claim:

1. A fixed resistor of sheet form having a pair of opposed marginal edges provided with current feed points defining a current axis between said points, at least one of said marginal edges being extended as a pointed tapping projection at an acute angle with respect to said axis. 25

2. A fixed resistor as set forth in claim 1 wherein said projection is extended at an angle in the range of 30 to 30 45 degrees and the bisector of said projection intersects said current axis at a point intermediate said current feed points.

3. A fixed resistor as set forth in claim 2 wherein said tapping projection is bounded by concavely recessed marginal edges of said resistor. 35

4. A fixed resistor as set forth in claim 3 having the form of a rectangle from each side of which a convex segment has been removed to form a concavely curved marginal edge and wherein said resistor is symmetrical about said current axis.

5. A fixed resistor as set forth in claim 4 wherein said curved marginal edges are defined by circular arcs.

6. A fixed resistor as set forth in claim 3 formed as a self-supporting homogenous body having a parallel-sided recess formed at each current feed point, the sides of the recess being spaced to permit axial engagement of the resistor with another in interlocking relation.

7. A fixed resistor as set forth in claim 3 wherein each element of a train of series-connected resistors comprises a film of resistive material adhered to a common supporting base.

8. A fixed resistor as set forth in claim 4 wherein the points of tapping projections lying opposite each other with respect to said current axis are electrically ganged by a conductor.

9. A fixed resistor as set forth in claim 8 wherein said resistor is symmetrical about an axis at right angles to said current axis.
